A CORPORATION OF DELAWARE

FLUID-FUEL-BURNER CONTROL

Application filed May 7, 1927. Serial No. 189,482.

The object of my invention is to provide a simple and efficient means for automatically controlling the action of a fluid-fuel burner so that it may be depended upon to permit 5 automatic normal operations of the burner but will prevent delivery of fuel in all cases of accidental failure of ignition or combustion.

The accompanying drawing illustrates my 10 invention diagrammatically.

In the drawings, 10 and 11 indicate the main lead lines and T indicates a room thermostat and/or other common mechanism for controlling flow of current to wire 12. Connected with wire 12 is the leaf 13 of a warp switch W which is normally held in contact with terminal 14, against the bias of spring 15 by the bi-metallic blade 16 of the warp switch, said blade being electrically insulated 20 from leaf 13.

Electrically connected to blade 16 is one end of the heating coil 17 of the warp switch W, the opposite end of said heating coil being connected by a wire 18 with terminal 14 25 and with a terminal 19 in the hot end of a mercury tube circuit breaker 20 which is part of a combustion control device C sensitive to combustion conditions adjacent the burner.

Paired with terminal 19 is a terminal 21 which is electrically connected to a terminal 22 in the cold end of breaker 20, and to blade 16 by a wire 23.

Paired with terminal 22 in the cold end of breaker 20 is a terminal 24 connected by wire 25 with the stator 26 of a supplemental valve motor VM, said stator being connected by wire 27 to a wire 28 which is connected to lead 10.

The rotor of valve motor VM is connected by a reducing train of gears 29 to a plunger 30 which opens and closes fuel valve 31 which is in the fuel supply line. Plunger 30 45 is biased to valve-closing position, against the rotor of motor VM, by a spring 32.

Connected to plunger 30 is a pivoted carrier 40 upon which are supported two mercury tube circuit breakers 41 and 42, the 50 arrangement being such that when the fuel

valve is closed both circuit breakers will be in open position.

Circuit breaker 41 comprises two terminals 43 and 44, terminal 44 being connected to wire 12 and terminal 43 being connected by wire 45 with the fuel motor M, said fuel motor being also connected through wire 28 to lead 10. 55

Circuit breaker 42 comprises two terminals 52 and 53. Terminal 52 is connected by wire 54 with wire 25 and therefore with stator 26 and terminal 24 of combustion control C. Terminal 53 is connected by wire 55 with wire 23 and therefore with terminals 21 and 22 of combustion control C and with blade 16 of switch W. 60

Electrical ignition means I comprises, in the present diagram, sparking means 60 and electrical pilot gas valve 61 which are connected by wire 62 with lead 10 and by wire 63 with terminal 64 of a mercury tube 65 on the pivoted carrier 66 of the ignition circuit breaker IS. 70

Carrier 66 is biased to circuit-opening position and this bias is time-controlled by the dash-pot D. Carrier 66 is moved to circuit-closing position by a one-way driving connection 67 carried by plunger 30. Paired with terminal 64 is a terminal 68 which is connected by wire 69 with wire 12 or in any 75 other suitable manner to lead 11. 80

The operation is as follows:

The parts are shown in cold position.

Upon call for heat by thermostat T the ignition mechanism is immediately energized 85 and a circuit 11—T—12—13—14—18—17—16—23—22—24—25—26—27—28—10 is established to energize the supplemental valve motor VM, thereby opening the fuel valve 31, shifting circuit breakers 41 and 42 to closed position and releasing ignition circuit breaker IS. Shifting of circuit breaker 41 to closed position provides the circuit 11—T—12—44—43—45—M—28—10 for the fuel motor, whereupon delivery of fuel is started. 90

Shifting of circuit breaker 42 to closed position provides for the supplemental motor a maintaining circuit 11—T—12—13—14—18—17—16—23—55—53—52—54—25—26—27—28—10, thus making the supplemental 100

motor independent of the cold side of the combustion control C.

Within a predetermined time the ignition circuit breaker IS moves to open position, thereby breaking the ignition circuit. If proper ignition has occurred at the burner, within this time, combustion control C will be moved to its hot position, thus breaking circuit at 22-24 and making circuit at 19-21. Thereupon the circuit 11-T-12-13-14-18-19-21-23-55-53-52-54-25-26-27-28-10 is established to maintain the valve motor in actuated position but shunting out the heating coil 17.

If initial ignition does not take place within the time limit of the ignition circuit breaker IS, coil 17 will become heated and will warp blade 16 away from leaf 13 to permit a break at 13-14 so that spring 31 may return the fuel valve and breakers 41 and 42 to normal, thus deenergizing the fuel motor, and throwing the apparatus out of commission until manually reset. If combustion ceases for any cause while the room thermostat T is closed, the combustion control will return to cold position, thereupon reestablishing the circuit through the heating coil 17, whereupon said heating coil will serve to cause a break at 13-14 and the fuel motor will be de-energized and circuit breakers 41, 42 and 65 will be returned to normal.

If, for any reason, the combustion control fails to properly respond to heat at the burner, or if terminals 19 and 21 have been improperly connected when the combustion control is in cold position, flow of current through the supplemental motor for a predetermined time will heat coil 17 and cause a break at 13-14 so that the apparatus will be put out of commission until manually reset.

The details of construction of the fuel valve form the subject matter of my co-pending application Serial No. 111,154.

I claim as my invention:

1. In a control system for fluid-fuel burners, a fuel motor; a supplemental motor; a combustion-control circuit-breaker sensitive to combustion conditions adjacent the burner and comprising a cold-pair of terminals and a hot-pair of terminals; a warp switch; a power supply circuit for the supplemental motor through the warp switch, its heating coil, and the cold side of the combustion-control; a maintaining circuit for the supplemental motor through the warp switch, the hot-side of the combustion-control and a circuit-breaker actuated by the supplemental motor, shunting out the heating coil; an energizing circuit for the fuel motor comprising a circuit-breaker moved to closed position by the supplemental motor.

2. In a control system for fluid-fuel burners, a fuel motor; a supplemental motor; a combustion-control circuit-breaker sensitive to combustion conditions adjacent the burner

and comprising a cold-pair of terminals and a hot-pair of terminals; a warp switch; a power supply circuit for the supplemental motor through the warp switch, its heating coil, and the cold side of the combustion-control; a maintaining circuit for the supplemental motor through the warp switch, the hot-side of the combustion-control and a circuit-breaker actuated by the supplemental motor, shunting out the heating coil; an energizing circuit for the fuel motor comprising a circuit-breaker moved to closed position by the supplemental motor; electrical ignition means and an energizing circuit therefor comprising a circuit-breaker time-biased to open position; and a one-way connection between the supplemental motor and said ignition circuit-breaker for moving said ignition circuit-breaker to normal closed position.

3. In a control system for fluid-fuel burners, a fuel motor; a supplemental motor; a reciprocable element driven in one direction through a reducing train from said supplemental motor; means biasing said reciprocable member in opposition to the supplemental motor; a combustion-control circuit-breaker sensitive to combustion conditions adjacent the burner and comprising a cold-pair of terminals and a hot-pair of terminals; a warp switch; a power supply circuit for the supplemental motor through the warp switch, its heating coil, and the cold side of the combustion-control; a maintaining circuit for the supplemental motor through the warp switch, the hot-side of the combustion-control and a circuit-breaker actuated by the reciprocable member, shunting out the heating coil; an energizing circuit for the fuel motor comprising a circuit-breaker moved to closed position by the reciprocable member.

4. In a control system for fluid-fuel burners, a fuel motor; a supplemental motor; a reciprocable element driven in one direction through a reducing train from said supplemental motor; means biasing said reciprocable member in opposition to the supplemental motor; a combustion-control circuit-breaker sensitive to combustion conditions adjacent the burner and comprising a cold-pair of terminals and a hot-pair of terminals; a warp switch; a power supply circuit for the supplemental motor through the warp switch, its heating coil, and the cold side of the combustion-control; a maintaining circuit for the supplemental motor through the warp switch, the hot-side of the combustion-control and a circuit-breaker actuated by the reciprocable member, shunting out the heating coil; an energizing circuit for the fuel motor comprising a circuit-breaker moved to closed position by the supplemental motor; electrical ignition means and an energizing circuit therefor comprising a circuit-breaker time-biased to open position; and a one-way connection between the supplemental motor and

said ignition circuit-breaker for moving said ignition circuit-breaker to normal closed position.

5. A control system having the characteristics specified in claim 1 wherein the motor-actuated circuit-breaker connected to the supplemental motor is connected to the cold side of the combustion-control and to the heating coil in such manner as to provide a heating current for said coil with the combustion control in cold position.

10 6. A control system having the characteristics specified in claim 1 and embodying a fuel valve actuated by the supplemental motor and controlling flow of fuel relative to the burner.

15 7. A control system having the characteristics specified in claim 2 wherein the motor-actuated circuit-breaker connected to the supplemental motor is connected to the cold side of the combustion-control and to the heating coil in such manner as to provide a heating current for said coil with the combustion-control in cold position.

20 8. A control system having the characteristics specified in claim 3 wherein the motor-actuated circuit-breaker connected to the supplemental motor is connected to the cold side of the combustion-control and to the heating coil in such manner as to provide a heating current for said coil with the combustion-control in cold position.

25 9. A control system having the characteristics specified in claim 4 wherein the motor-actuated circuit-breaker connected to the supplemental motor is connected to the cold side of the combustion-control and to the heating coil in such manner as to provide a heating current for said coil with the combustion-control in cold position.

40 10. A control system having the characteristics specified in claim 2 and embodying a fuel valve actuated by the supplemental motor and controlling the flow of fuel relative to the burner.

45 11. A control system having the characteristics specified in claim 3 and embodying a fuel valve actuated by the supplemental motor and controlling the flow of fuel relative to the burner.

50 12. A control system having the characteristics specified in claim 4 and embodying a fuel valve actuated by the supplemental motor and controlling the flow of fuel relative to the burner.

In witness whereof, I PAUL F. SHIVERS have hereunto set my hand at Wabash, Indiana, this 30th day of April, A. D. one thousand nine hundred and twenty-seven.

PAUL F. SHIVERS.
